DUPLEX PUMP

Karl P. Neilsen, Long Beach, Calif.

Application February 29, 1936, Serial No. 66,363

3 Claims. (Cl. 103—187)

This invention relates to a novel duplex pump in which a pair of superposed pumping chambers simultaneously take in and discharge on each stroke of the pump.

5 An object of my invention is to provide a novel duplex pump including one traveling piston and one stationary piston, the pumping chambers traversed by each piston being so arranged that fluid is drawn past the stand valve into both of the pumping chambers on the upstroke of the pump, and both of the chambers discharging on the downstroke of the pump.

Another object is to provide a novel bottom discharge valve in a duplex pump of the character stated, the lower pumping chamber discharging thru said bottom discharge valve.

Still another object is to provide a pump of the character stated which will not readily sand up and which will pump a large quantity of liquid on each stroke thereof.

Other objects, advantages and features of invention may appear from the accompanying drawings, the subjoined detailed description, and the appended claims.

25 In the drawings:

Figure 1 is a fragmentary longitudinal sectional view of the upper portion of my pump.

Figure 2 is a fragmentary longitudinal sectional view of the central portion of my pump.

30 Figure 3 is a fragmentary longitudinal longitudinal sectional view of the lower portion of my pump.

Figure 4 is a fragmentary longitudinal view of the bottom discharge valve.

35 Figure 5 is a sectional view taken on line 5—5 of Fig. 6.

Figure 6 is a fragmentary longitudinal sectional view of another type of bottom discharge valve.

Figure 7 is a sectional view taken on line 7—7 of Fig. 6.

40 Figure 8 is a fragmentary side elevation of the stationary barrel showing the dog clutch.

Figure 9 is a fragmentary longitudinal sectional view of the upper portion of a modified form of duplex pump.

Figure 10 is a fragmentary longitudinal sectional view of the center portion of the modified pump.

Figure 11 is a fragmentary longitudinal sectional view of the lower portion of the modified pump.

Figure 12 is a diagrammatic view of the pump shown in Figures 1 to 3.

Figure 13 is a diagrammatic view of the pump shown in Figures 9 to 12.

Referring more particularly to the drawings, the numeral 1 indicates the tubing in which my pump is placed and thru which the liquid is carried to the surface. It is to be noted that in the drawings I have shown the tubing on one side only, to save space.

5 My pump comprises a top cage 2 which is attached to the lower end of a string of sucker rods—not shown. A ball valve 3 is mounted in the cage 2 for the purpose of controlling the upper pumping chamber, as will be further described. A sub 4 screws into the cage 2, and the traveling barrel 5 screws onto the sub 4. A reducer 6 screws into the lower end of the traveling barrel 5 and the lower extension of the traveling barrel 5 is attached to the reducer 6. A traveling piston 8 is attached to the lower end of the member 7. The piston 8 reciprocates in a stationary barrel 9. The piston 8 is provided with outer packing 10 and inner packing 11. This packing may be either metallic or non-metallic, as is found most desirable.

10 A pull nut 12 is attached to the upper end of the stationary barrel 9, and the lower extension of the traveling barrel 7 extends thru this nut. A stationary pull tube 13 extends centrally in the pump and the piston 8 reciprocates over the pull tube.

15 A stationary piston 14 is attached to the upper end of the tube 13 and this last named piston is provided with packing 15 which bears against the inside of the traveling barrel 5. This packing 15 also may be either metallic or non-metallic. The piston 14 is hollow and the cage 16 is attached to the upper end of said piston. A ball valve 17 in the cage 16 controls the movement of fluid thru the piston 14 and into the upper pumping chamber 18, as will be further described.

20 The lower end of the pull tube 13 screws into the fitting 19 and this fitting, in turn, screws into a lower discharge valve housing 20. A sub 21 connects the housing 20 and the standing valve cage 22. A ball valve 23, of usual construction, is positioned within the cage 22. The cage 22 is attached to a spring hold down shoe 24 which shoe releasably engages the annular shoulder 25 in the lower end of the tubing 1. Thus, it will be evident that the shoe 24, the standing valve cage 22, the bottom discharge valve housing 20, the pull tube 13 and the piston 14 are held stationary within the traveling barrel 5 and its lower extension 7.

25 The traveling piston 8 operates in a lower pumping chamber 26. The fitting 19 is pro-

vided with a plurality of horizontally extending ports 27 which lead from the inside of the fitting into the pumping chamber 26. The lower discharge valve housing 20 is provided with a transverse discharge port 28 which port extends into the annular discharge space 29 in the tubing 1. A vertical intake port 30 in the housing 20 is controlled by the ball check 31. The housing 20 is also provided with by-pass ports 32 which 10 permit the fluid to pass thru the housing and thence upwardly into the lower pumping chamber 26, as will be further described.

The operation of the pump shown in Figs. 1 to 8, inclusive, is as follows:

15 Assuming that the pump is starting on the upstroke. The sucker rods attached to the cage 2 are pulled upwardly. The ball 3 is seated. A partial vacuum is created in the upper pumping chamber 18 and fluid is drawn past the foot 20 valve 23, thence upwardly in the ports 32, then into the pull tube 13, and finally past the ball check 17 into the upper pumping chamber 18. At the same time, the lower pumping chamber 26 is operating to draw fluid in also past the foot 25 valve 23, thence thru the ports 32 and 27, thereby filling the lower pumping chamber with fluid.

On the downstroke, the ball 17 is seated. The liquid is forced upwardly past the ball check 3 and thence into the tube 1. At the same time 30 that liquid is being discharged from the upper pumping chamber, the lower pumping chamber is forcing liquid out thru the ports 27, thence downwardly thru the passages 32, and since the foot valve 23 is seated, the liquid will be forced 35 upwardly, unseating the ball 31, and the liquid will then pass outwardly thru the horizontal ports 28 into the tubing 1 and thence to the surface. Part of the liquid may also pass upwardly thru the pull tube past the ball 17.

40 Liquid would find its way below the stationary piston 14 and to prevent this accumulated liquid from interfering with the operation of the pump, I provide relief holes 33 adjacent the lower end of the traveling barrel 5. Relief holes 34 are 45 provided in the extension of the traveling barrel 7 adjacent the lower end for the purpose of preventing accumulation of sand above the traveling piston 8, and also to relieve the space between the pull tube 13 and the extension of the 50 traveling barrel 9 and the barrel 7. These various holes just described are for the purpose of preventing accumulation of sand in the space between various moving parts and also to relieve these spaces from any accumulation of liquid.

55 As shown in Fig. 8, I might provide a dog clutch 36 which will couple the pull nut 12 and the fitting 6, so that the stationary barrel 9 can be held from rotating in order to effectively screw up the rods.

60 As shown in Fig. 4, the bottom discharge valve can be inverted from the position shown in Figs. 3 and 6, i. e., the housing 37 is provided with a central upwardly extending tube 38. The ball 39 seats upwardly in the tube 38. The horizontal ports 40 are the same as previously described and perform the same function.

When the ball 39 seats upwardly instead of downwardly—as previously described in Fig. 6,—the pressure of the fluid in the tubing will hold 70 the ball 39 seated. When the bottom pumping chamber 26 is discharging, the pressure of the discharged liquid will unseat the ball 39, thus forcing the liquid out thru the ports 40 and into the tubing 1.

75 In Figs. 9, 10 and 11, I have disclosed a modi-

fied form of duplex pump similar in construction and operation to the pump previously described, with the exception that the bottom discharge valve is eliminated in the modification. The tubing 41 is provided with a coupling 42 which 5 coupling is spaced above the bottom of the well, and the purpose of this coupling will be further described.

A lock fitting 43 is attached to the lower end of the tubing 41 which fitting is engaged by the 10 locking shoe, as will be further described.

My pump includes a top cage 44 to which the lower end of the sucker rods are attached. A ball check 45 is seated in the cage in the usual and well known manner. A traveling barrel 46 15 is attached to the cage 44 and extends downwardly therefrom. A traveling piston 47 is mounted on the lower end of the barrel 46 and this piston reciprocates in the stationary barrel 48. The stationary barrel screws onto a sub 49 20 and the locking shoe 50 screws into the sub 49 and depends therefrom. The locking shoe engages the fitting 43 for the purpose of holding certain parts of the pump stationary in the tub- 25 ing.

A standing valve 51 is mounted on the sub 49 for the purpose of controlling the liquid as it enters the pump. The valve 51 is enclosed by a cage 52. A pull tube 53 is attached to the cage 52 and extends upwardly in the pump and 30 thru the traveling piston 47. The piston 47 is provided with suitable metallic or non-metallic packing on the inside against the pull tube 53 and on the outside against the stationary barrel 48. 35

A stationary piston 54 is mounted on the upper end of the pull tube 53. The stationary piston is hollow to permit liquid to move thru it. A cage 55 is mounted on the upper end of the piston 54 and a ball check 56 in the cage controls 40 the liquid passing into the upper pumping chamber 57.

A lower pumping chamber 58 is provided below the traveling piston 47. A collar 59 is mounted on the upper end of the stationary barrel 43 and an expansion ring 60 is mounted in the collar and presses outwardly against the coupling 42. This packing seals the tubing and prevents sand, and the like, from moving downwardly in the tube around the outside of the 50 stationary barrel 48.

Relief ports 61 are provided in the traveling barrel 46 above the traveling piston 47. The operation of the last described pump is as follows:

Starting with the upstroke, the ball 45 is seated, liquid is drawn past the standing valve 51, thence upwardly thru the pull tube 53, then past the check valve 56 and into the upper pumping chamber 57. At the same time, liquid is drawn past the standing valve 51 thru the cage 52 and into the lower pumping chamber 58. 60

On the downstroke, the valve 51 is seated, the valve 45 is unseated, the liquid in the chamber 57 is forced out past the valve 45 and into the tubing 41. The liquid in the chamber 53 is forced upwardly thru the pull tube 53 and as soon as the pressure of this liquid overcomes the head of liquid in the tubing, the valve 56 will be unseated and the liquid will then pass around 70 the valve 56, thence into the chamber 57, then past the valve 45 and into the tubing.

Having described my invention, I claim:

1. A duplex pump for wells, a tubing in which the pump is positioned comprising a standing 75

valve, a locking shoe depending from the standing valve, said locking shoe being releasably held in the tubing, a bottom discharge valve housing fixedly mounted on the standing valve and arranged above said standing valve, a valve in said housing, said housing having ports opening into the tubing, said valve controlling the flow from within the pump to said ports, a stationary barrel mounted on the standing valve and rising therefrom, a stationary pull tube mounted on said housing and rising therefrom, a stationary piston mounted on the upper end of the pull tube, a traveling barrel extending over the stationary piston and arranged within the stationary barrel, a traveling piston mounted on the lower end of the traveling barrel, said traveling piston surrounding the pull tube, said pump having a lower pumping chamber below the traveling piston and within the stationary barrel, said pull tube having ports therein opening into said pumping chamber, a check valve mounted on the upper end of the traveling barrel, and clutch means arranged between the traveling barrel and a stationary barrel, said clutch means being engageable in the lowered position of the traveling barrel, and closure means between the tubing and the stationary barrel, said closure means being arranged below the bottom discharge valve.

2. A duplex pump for wells, a tubing in which the pump is positioned comprising a standing valve, a locking shoe depending from the standing valve, said locking shoe being releasably held in the tubing, a bottom discharge valve housing fixedly mounted on the standing valve and arranged above said standing valve, said housing having a transverse port therein opening into the tubing and a vertical port extending into the transverse port, a valve in the vertical port, said valve controlling the flow from within the pump to said ports, a stationary barrel mounted on the standing valve and rising therefrom, a stationary pull tube mounted on the housing and rising therefrom, a stationary piston mounted on the upper end of the pull tube, a traveling barrel extending over the stationary piston and

arranged within the stationary barrel, a traveling piston mounted on the lower end of the traveling barrel, said traveling piston surrounding the pull tube, said pump having a lower pumping chamber below the traveling piston and within the stationary barrel, said pull tube having ports therein opening into said pumping chamber and a check valve mounted on the upper end of the traveling barrel and closure means between the tubing and the stationary barrel, and clutch means arranged between the traveling barrel and the stationary barrel, said clutch means being engageable in the lower position of the traveling barrel.

3. A duplex pump for wells, a tubing in which the pump is positioned comprising a standing valve, a locking shoe depending from the standing valve, said locking shoe being releasably held in the tubing, a bottom discharge valve housing fixedly mounted on the standing valve and arranged above said standing valve, a valve in said housing, said housing having ports opening into the tubing, said valve controlling the flow from within the pump to said ports, a stationary barrel mounted on the standing valve and rising therefrom, a stationary pull tube mounted on said housing and rising therefrom, a stationary piston mounted on the upper end of the pull tube, a traveling barrel extending over the stationary piston and arranged within the stationary barrel, a traveling piston mounted on the lower end of the traveling barrel, said traveling piston surrounding the pull tube, said pump having a lower pumping chamber below the traveling piston and within the stationary barrel, said pull tube having ports therein opening into said pumping chamber, a check valve mounted on the upper end of the traveling barrel, a dog clutch arranged between the traveling barrel and the stationary barrel, said dog clutch including a female member on one barrel and a male member on the other barrel, said dog clutch being engageable in the lower position of the traveling barrel and closure means between the tubing and the stationary barrel.

KARL P. NEILSEN.
